UNITED STATES PATENT OFFICE.

CAMILLE A. FAURE AND GEORGE TRENCH, OF FAVERSHAM, ASSIGNORS
TO THE COTTON POWDER COMPANY, (LIMITED,) OF WESTMINSTER,
ENGLAND.

SIGNALING-CARTRIDGE.

SPECIFICATION forming part of Letters Patent No. 231,705, dated August 31, 1880.

Application filed May 24, 1880. (No model.) Patented in England June 25, 1878.

To all whom it may concern:

Be it known that we, CAMILLE ALPHONSE FAURE and GEORGE TRENCH, both of Faversham, in the county of Kent, England, have 5 invented new and useful Improvements in Shells and Rockets, mainly applicable for signaling purposes, which improvements are fully set forth in the following specification, reference being had to the accompanying drawings.

This invention relates to contrivances for signaling, to be used at sea or on land as distress-signals, and also on festive displays, and whereby a loud report is obtained simply or 15 in combination with a display of stars or other luminous arrangement. For these purposes we form in the following manner a shell, to be fired upward from a small mortar or socket.

The shell consists of, first, a cylindrical envelope of tin, brass, card-board, or such like substance; second, a bottom plug fitting tightly to the cylindrical envelope, and which bottom plug is perforated with a hole, into which is rammed some fuse-powder, and thus 25 constitutes a time-fuse; third, the exploding-charge, which consists, generally, in a cylinder of powders that require a detonator to properly explode them—viz., gun-cotton, cotton-powder, or lithofracteur, and such like substances.

The detonator may be fixed into the exploding-charge by the makers during the manufacture of the shots, or may be introduced by the consumer at any time before using such 35 shots. When it is desired to display a luminous artifice, this artifice must necessarily be blown or shot out of the shell before the explosion of the sounding-charge. This can be done by separating the exploding-charge, 40 which lies near the time-fuse, at the bottom of the shell, from the group of stars or other artifice by a disk obtained by the compression of ordinary grained gunpowder. This gunpowder disk catches fire from the time-fuse 45 through a central hole reserved in the middle of the exploding-charge, the effect being that the stars or luminous artifice is blown off

through the top orifice of the envelope or shell, which, for that purpose, is fitted with a cover much looser than the bottom plug. The mode of firing the shot thus made from the 50 socket may be according to well-known means—viz., by pouring the charge of ordinary gunpowder inside the socket and firing from the touch-hole with a Bickford fuse or 55 with a friction-tube; but we prefer to attach the propelling-charge of gunpowder to the bottom plug of the shot itself. This charge of gunpowder is inclosed in a thin water-proof bag, and may be pricked through the touch-hole.

For signals intended to be used at sea we sometimes dispense with the touch-hole in the socket as being liable, from non-usage, to get corroded or painted up and unavailable 65 in an emergency. The shot itself carries the touch-hole—that is, a firing-tube (into which the friction-tube can be lodged) is laid through the length and center of the shot. It reaches into the propelling-powder in the bag or bottom 70 and through the top plug or cover, and as the shot is about of same length as the bore of the socket the top of the firing-tube is accessible when the shot is in its place inside the socket.

Signal-rockets which will display a luminous arrangement, such as stars or such like, and give a sound-signal by the use of a gun-cotton or detonating charge, may also be formed in a similar manner by replacing the 80 propelling-charge in the signals described above by an ordinary rocket. The rocket and signal can evidently be built together in one envelope.

The detonator to be used in conjunction 85 with such exploding or sounding charges that are propelled by means of gunpowder we form of a tube of copper filled half-way up with the usual detonating composition, and the other half of the tube we fill with fuse-powder, so as to 90 make the detonator itself a time-fuse. This is intended to give great security to the person who fires the shot from the socket, as in case the bottom plug should be defective the fire

from the propelling-charge might then reach immediately the inside of the shell or shot, and would thus, in the absence of the fusing-powder in the detonator, cause the mortar to be blown to pieces.

The signal shells and rockets may be arranged to give two or more reports by the employment of two or more detonating-charges, each fitted with their detonators and time-fuse, and so separated by means of disks of gunpowder that they are scattered like ordinary stars, and thus explode distinctly at regulated intervals of time.

In order that our invention may be most fully understood and readily carried into effect, we will proceed to describe the drawings hereunto annexed.

In the drawings, Figure 1 shows a shell for producing sound. It is formed of the tin case A. Into this is driven tight a wood or metallic plug, B, perforated with a central hole, C, into which is rammed some fuse powder. D is the sounding-charge, and E the detonator for exploding the same.

F is the wooden cap, and G is a small charge of common gunpowder inclosed in a water-proof bag secured to the shell by pasting or otherwise. This shell so completed is to be placed in a metallic socket, as shown in Figs. 6 and 7. It is fired by a friction-tube or fuse inserted through the touch-hole. It ascends in the air by the effect of the bottom charge of gunpowder, which also ignites the time-fuse in the plug, and this, in turn, ignites the detonator and fires the charge.

Fig. 2 shows the detonator. It is made of a copper shell filled about half-way with a composition of fulminate of mercury, m, and completed by a charge of meal-powder, n.

Fig. 3 shows a signal or shell for producing sound and light. A is the tin shell. B is a metallic plug or bottom securely fixed in the tin shell by soldering or otherwise. C is a copper time-fuse soldered into the plug B. D is the sounding-charge, formed of a cartridge of cotton-powder or such like explosive. E is the detonator, as above described. F is the top cap, so fastened as to be blown out by the pressure from within. G is the propelling-charge, as above described. It is inclosed in a water-proof bag, securely fixed to the main body of the shell. H is a group of stars or light-producing materials, and I is a central tube soldered to the bottom plug, and through which the bottom gunpowder-charge is ignited. The firing is produced by a friction-tube or by a Bickford fuse passed into the central tube. This shell is fired from the socket, as before said, and shown in Figs. 6 and 7; but in this case no touch-hole is required. The time-fuse C catches fire by the effect of the explosion of the gunpowder-charge, and at the proper altitude communicates fire to the group of stars. The top plug gets

blown out by the pressure from within, and the stars fall out. The detonator has also caught fire, and after the stars have been expelled the fire reaching the fulminating composition of the detonator the sounding-charge is exploded. It will be noticed that the sounding-charge is molded with a central hole for the passage of the central tube and for the communication of the fire from the bottom time-fuse to the group of stars or lighting material.

Fig. 4 is a shell similar to the above, and is to produce sound and light likewise; but in this the central tube is dispensed with and the initial firing is produced through the touch-hole in the socket.

Fig. 5 shows a shell for producing two distinct explosions or sounds. It is similar to the above, the group of stars being replaced by a second sounding-charge supplied likewise with a detonator. The two charges are separated by a disk of gunpowder, which pushes the top sounding charge or cartridge out of the shell, and as the two detonators are differently timed two distinct explosions are produced. A disk of gunpowder is also placed between the top cartridge and the top plug to facilitate the ignition of the detonator in this top cartridge. This top gunpowder disk may be replaced by a group of stars or other light-producing material, if required.

Fig. 6 shows a socket for firing these shells. It is intended to be fixed into the rail of a ship, as shown.

Fig. 7 shows a socket intended to be fixed onto the deck of a ship or upon a piece of timber ashore.

Instead of firing these shells from their sockets, we sometimes use ordinary rockets as the means of propulsion. In this case the gunpowder propelling-charge at the bottom of the shell is replaced by the body of the rockets.

We are well aware that various improvements have before been made in pyrotechnic cartridges, signaling-rockets, &c., and therefore limit our claim to subject-matter such as presently to be defined, our shells and rockets being designed to produce loud reports and having detonating-charges and detonators.

We claim as of our own invention—

1. The combination of the cylindrical envelope closed at top and bottom, respectively, with a head-cap and with a plug carrying a time-fuse, and which also contains balls or blocks of composition for giving light when burning in the air, and a detonating-charge and a detonator which is formed partly as a time-fuse, whereby said balls or blocks may be ignited and thrown out before the detonating-charge is detonated by said detonator, substantially as hereinbefore set forth.

2. The combination of, first, a detonator composed of a thin metallic tube filled in part

with a detonating compound, such as fulminate of mercury, and in part with meal-powder; second, a molded charge of detonating compound with a cavity therein in which the detonator is received; and, third, an envelope incasing the detonating-charge and detonator, and closed at top with a head-cap and at

bottom with a plug carrying a time-fuse, substantially as hereinbefore set forth.
